(57) **CLAIM**

The ornamental design for a strain-relieving solar cell interconnect, as shown and described.

DESCRIPTION

FIG. 1 is a front, top, right side perspective view of the strain-relieving solar cell interconnect in accordance with the present invention;

FIG. 2 is a front view, the rear view being a mirror image thereof;

FIG. 3 is a top view, the bottom view being a mirror image rear view thereof;

FIG. 4 is a right side view, the left side view being a mirror image thereof;

FIG. 5 is the front view of FIG. 2 expanded seven times illustrating the detail thereof;

FIG. 6 is a right side view having segments 9A-9I thereof delineated by dashed lines for enlargement of each segment to show details as shown in subsequent right side views of FIGS. 7A-7I herein;

FIGS. 7A-7I are enlarged views of respective segments identified as 7A-7I shown in FIG. 6, the segments being enlarged nine times to illustrate the detail thereof;

FIG. 8 is a left side view having segments 9A-9I thereof delineated by dashed lines for enlargement of each segment to show details as shown in subsequent left side views of FIGS. 9A-9I herein; and,

FIGS. 9A-9I are partial views of segments 9A-9I identified in FIG. 8, the segments being expanded nine times to illustrate the detail thereof.

1 Claim, 13 Drawing Sheets
